UNITED STATES PATENT OFFICE.

JOHN WILLISON, OF CLEVELAND, OHIO, ASSIGNOR, BY MESNE ASSIGNMENTS, TO NATIONAL MALLEABLE AND STEEL CASTINGS COMPANY, OF CLEVELAND, OHIO, A CORPORATION OF OHIO.

DRAFT AND BUFFING MECHANISM FOR RAILWAY CARS.

Application filed May 18, 1923. Serial No. 639,767.

To all whom it may concern:

Be it known that I, JOHN WILLISON, a subject of the King of Great Britain, and a resident of Cleveland, Cuyahoga County, Ohio, have invented new and useful Improvements in Draft and Buffing Mechanism for Railway Cars, of which the following is a specification, reference being had to the accompanying drawings, in which:

10 Fig. 1 is a plan, partly in section, of draft and buffing mechanism embodying my invention applied to the underframing of a railway car; Fig. 2 is a section on line II—II of Fig. 1; Fig. 3 is a section on line 15 III—III of Figs. 1 and 2; Fig. 4 is a plan, partly in section, of a modified form of my invention; Fig. 5 is a longitudinal section on line V—V of Fig. 4; and Fig. 6 is a section on line VI—VI of Fig. 4.

20 My invention relates to draft and buffing mechanism for railway cars, and particularly to draft and buffing mechanism for use on cars of small tonnage, such cars, for instance, as are of the Anglo-Indian type.

25 To this end my invention is directed to a type of draft and buffing mechanism capable of being applied to cars of existing design, such, for instance, as cars of the Anglo-Indian type, which is adequate to take up 30 the normal buffing and draft stresses to which such cars are subjected. My invention provides a spring cushioning mechanism which is connected to the car coupler by a novel arrangement later to be described.

35 My invention also comprises the various features which I shall hereinafter describe and claim.

Referring to the drawings, 2 indicates the 40 end sill of the car and 3 the two longitudinal center sills. Between the center sills 3 and a short distance to the rear of the end sill 2 is a cross member 4 consisting of the plate 4^a and channel 4^b, which connects the center sills 3. The cross member 4 is preferably 45 braced against buffing stresses by the reinforcing angles 5, which are riveted to the center sills 3 and the cross member 4.

A carrier casting 7 is secured to the front 50 face of the end sill 2, which in addition to supporting the coupler 8 provides means for limiting its lateral play.

The car coupler 8, which I have shown of the type described in my Patent No. 1,201, 665, dated October 17, 1916, preferably has

buffing horns 9 intended to strike against 55 the front face of the carrier casting 7. The carrier casting 7 has a central aperture 10 through which the shank 11 of the coupler is inserted. The rear end of the coupler shank is provided with an elongated slot 12 60 which extends through the shank from top to bottom.

The draft mechanism comprises an equalizing casting 13 which bears against the forward face of the cross member 4. The 65 equalizer 13 has forwardly extending horizontal projections 14 which form a bearing between them for the rear end of the coupler butt, and have registering apertures 15 70 for the insertion of a connecting pin 16 which extends through the apertures 15 and through the elongated slot 12 in the coupler shank. To keep the horizontal projections 14 from spreading, and also to hold the pin 16 in position in the apertures 15 and slot 75 12, a pair of straps 17 are bolted therearound. Extending rearwardly through the rear side of the equalizer 13 and through the cross member 4 are apertures 18 for the 80 spring carrying bolts 19, which are arranged in twin, and upon which, to the rear of the cross member 4, are mounted the compression springs 20. The bolts 19 at their forward ends are secured to the equalizer 13 by the vertically extending pins 21. The 85 springs 20 at their rear ends bear against washers 19^a on the bolts 19, and at their forward ends against the rear face of the buffing follower 22.

The buffing mechanism comprises a buffing follower 22, which is arranged on the rear side of the cross member 4, and has a centrally located extension 23 which projects forwardly through registering central openings in the centers of the cross member 4 95 and of the rear wall of the equalizer 13. The forward end 23^a of this extension 23 is concave and fits against the convex rear face of the coupler butt.

Attached to the under side of the center 100 sills is a bottom plate 24, which has an aperture 24^a therein to provide access to the draft connections. The buffing member 22 also preferably has sockets 25 on its rear face which are intended to be used in connection 105 with the supplemental buffing mechanism shown in Figs. 4, 5 and 6, and is later to be described.

The operation of my device is as follows: In buffering the stresses are transmitted directly from the convex face at the rear end of the coupler shank 11 to the concave face 23^a at the forward end of the buffering follower 22, and as the coupler 8 moves rearwardly it will push the buffering follower 22 rearwardly against the resistance of the springs 20, the rear ends of which are held immovable by the washers 19^a at the rear ends of the bolts 19. During this operation the equalizer 13 remains stationary because of its bearing against the forward side of the cross member 4, the movement of the coupler to the rear relative to the equalizer 13 and pin 16 being permitted by the elongated slot 12 in the rear end of the coupler shank.

In draft, as the coupler pulls forwardly, the pulling stresses are transmitted through the pin 16 to the equalizer 13 and from the spring bolts 19 and washers 19^a to the springs 20, so that as the bolts 19 pull forwardly the pressure is transmitted to the car through the cross member 4 from the buffering follower 22, which holds the forward ends of the springs against forward movement and hence takes up the stresses transmitted through the springs. The foregoing arrangement is of particular advantage, since it permits the application of my invention to cars of the present Anglo-Indian type, and also utilizes the same arrangement of springs for buffering and draft as is now in use for draft alone.

Where further spring capacity is required, the arrangement shown in Figs. 4, 5 and 6 may be employed. In this form the buffering mechanism shown in the preferred form is supplemented by the following buffering apparatus:

On the rear side of the buffering follower 22 are sockets 25 in which the forward ends of the columns 26 seat. The rear ends of the columns 26 are screw-threaded and pass through the forward end of the casing 27, which is arranged to telescope within the casing 28. The casing 27 has a central rearwardly directed extension 29 against which the forward end of a rearwardly extending plunger 30 abuts. About the plunger 30, with its forward end bearing against the extension 29, is a flanged sleeve 31, the flange 32 of which bears against the forward end of a buffer spring 33. The rear end of the spring 33 bears against the rear end of the casing 28. Butted against and secured to the rear of the casing 28 is another oppositely facing casing 34, which has a supporting engagement with an inner casing 35. The rear end of the casing 28 and the forward end of the casing 34 are apertured for the plunger 30, which extends for some distance into the casing 35. At its rear end the casing 35 is riveted to a cross member 36,

which is secured to the center sills 3. The plunger 30 has at its rear end an enlarged head 37, and between this head and the rear end of the casing 35 is a second buffering spring 38. It will be seen that the casings 27 and 28 are arranged in tandem relative the casings 34 and 35.

The mechanism just described is inoperative during draft, as it is engaged only by the buffering follower 22 and is not connected with the draft member 13. During buffering, as the follower 22 moves to the rear it will carry with it the columns 26 and the casing 27, and through the central extension 29 of the casing 27 the buffering stresses are carried by the sleeve 31 and the plunger 30, respectively, to the supplemental buffering springs 33 and 38.

This arrangement provides additional buffering capacity which, if desired, may be employed in connection with the draft and buffering mechanism shown in Figs. 1, 2 and 3. Apparatus of the character described is particularly useful where comparatively heavy cars are used, for the reason that the buffering stresses are generally greater than the draft stresses, and this form of my invention provides for the necessary additional buffering capacity.

The term and expressions which I have employed are used as terms of description and not of limitation, and I have no intention, in the use of such terms and expressions, of excluding any mechanical equivalents of the features shown and described, or portions thereof, but recognize that various structural modifications are possible within the scope of the invention claimed.

What I claim is:

1. In draft and buffering mechanism, a draft equalizing member having a flexible connection with a coupler shank, a plurality of springs flexibly connected to said draft member, and a buffering member interposed between said springs and said coupler shank.

2. In draft and buffering mechanism, a member rigidly secured to the framing of a car, a draft member and a buffering member, a plurality of springs flexibly connected to said draft member and in contact with said buffering member to hold said members normally in contact with said stationary member, and a coupler shank having a pivotal connection with said draft member whereby draft stresses are equally distributed to each of said springs.

3. In draft and buffering mechanism, a draft member attached to a coupler shank, a pair of bolts pivoted to the draft member, a spring mounted on each bolt and having a bearing against the rear end thereof, a buffering follower bearing at its forward end against the rear end of the coupler shank and at its rear end against the forward

- end of each such spring, and means attached to the frame of the vehicle for holding the draft member immovable during buffing and the buffing member immovable during draft.
4. In draft and buffing mechanism, a draft member attached to a coupler shank, a pair of bolts pivoted to the draft member, a spring mounted on each bolt and having a bearing at the rear end of the bolt, a buffing member forming a bearing for the forward end of each spring, a projection on the buffing member extending forwardly through the draft member to engage the rear end of the coupler shank, and means for holding the draft member immovable during buffing and the buffing member immovable during draft.
5. In draft and buffing mechanism, a draft member attached to a coupler shank, a buffing member having a bearing upon the coupler shank, spring mechanism arranged between portions of the buffing and draft members, and spring and plunger mechanism attached to the buffing member for taking up extra heavy buffing shocks.
6. In draft and buffing mechanism, a draft member, a buffing member and a spring interposed between said members to resist movement thereof, auxiliary buffing mechanism connected to said buffing member and comprising a plurality of springs, and plunger mechanism for compressing each of said springs independently upon rearward movement of said buffing member.
7. In draft and buffing mechanism, a draft member having a flexible slot and pin connection with a coupler shank, said connection being operative in draft and inoperative in buffing, the draft member having a plurality of rearwardly extending bolts pivoted thereto, a spring on each bolt having a bearing against the bolt at its rear end, and a buffing member engaged by the forward end of said springs and pivotally engaging the rear end of the coupler shank in buffing.
8. In draft and buffing mechanism, a draft member having a pivotal connection with a coupler shank, a pair of bolts pivoted to the draft member, springs on the bolts having bearings at the rear ends of the bolts, a buffing member pivotally engaging the rear end of the coupler shank in buffing and forming bearings for forward ends of the springs, a transverse portion of the underframing of the car forming at its rear side a bearing against which the buffing member is pressed in draft, and at its forward side a bearing against which the draft member is pressed in buffing.
9. In draft and buffing mechanism, a coupler shank, a draft member having a pair of forward projections, said shank and projections being apertured for reception of a pivot pin, a yoke embracing the said projections to hold the pivot pin in position and to prevent spreading of the said projections, spring mechanism attached to the draft member, a buffing member upon which the coupler shank and spring mechanism have a bearing, and means for rendering the draft member immovable in buffing and the buffing member immovable in draft.

JOHN WILLISON.
